[57] CLAIM

The ornamental design for the jewelry display board, as shown and described.

DESCRIPTION

FIG. 1 is a top plan view of my jewelry display board;
FIG. 2 is a front elevational view of my jewelry display board;

FIG. 3 is a side elevational view of my jewelry display board the opposite side being a mirror image thereof;

FIG. 4 is a rear elevational view of my jewelry display board; and,

FIG. 5 is a bottom plan view of my jewelry display board. The broken line showing jewelry is for illustrative purposes only and forms no part of the claimed design.
